CLAIM

The ornamental design for a door handle, as shown and described.

DESCRIPTION

FIG. 1 is a perspective view of a door handle showing our new design;

FIG. 2 is a left side view thereof;

FIG. 3 is a right side view thereof;

FIG. 4 is the top view thereof;

FIG. 5 is the bottom view thereof;

FIG. 6 is a front view thereof; and,

FIG. 7 is a rear view thereof.

The broken lines shown in the drawings represent portions of the door handle that form no part of the claimed design.

1 Claim, 7 Drawing Sheets
